UNITED STATES PATENT OFFICE.

MYRON A. TWITCHELL, OF KINGSLEY, IOWA.

ADJUSTABLE CULTIVATOR-SHOVEL.

SPECIFICATION forming part of Letters Patent No. 310,856, dated January 13, 1885.

Application filed April 5, 1884. (No model.)

To all whom it may concern:

Be it known that I, MYRON A. TWITCHELL, a citizen of the United States, residing at Kingsley, in the county of Plymouth and State 5 of Iowa, have invented certain new and useful Improvements in Cultivator-Shovels, of which the following is a description.

This invention relates to implements for cultivating the earth; and it has for its object 10 to provide a shovel or tooth for cultivators, which shall be capable of doing service with any one of its four sides or four corners forward, or with any side set at any desired angle of inclination to the line of travel.

15 To this end my invention consists in the construction and combination of parts forming a cultivator-shovel hereinafter described and claimed, reference being had to the accompanying drawings, in which—

20 Figure 1 is an inverted plan view of my shovel. Fig. 2 is a longitudinal vertical section of the same, showing the shovel inverted; and Fig. 3 is a transverse section in detail.

J represents the blade of the shovel in the 25 form of a trapezium whose major sides and transverse diameter, taken together, would form an equilateral triangle, and whose inner sides are each about two-thirds the length of a major side. This blade is a plate of steel concave in its front face, like a segment of a 30 spherical shell. Thus each of its four sides, which are sharpened as plowing-edges, are concave.

F is a shank having a socket in which the 35 standard E is held by a set-screw, m. This shank F is rigidly fixed to a beveled serrated wheel, G, which is centrally pivoted to the blade J, upon a screw-bolt, N, whereby the plate may be turned completely around, so 40 that any one of its four edges may be set at any angle with the line of travel.

H and I are buttons, each having a concave serrated edge fitted to engage the edge of the wheel G at any point of its circumference. Each of these buttons has a slot, L, through which and a hole in the plate J a screw-bolt, K, passes to hold the button to the plate. By means of the slot the button may be set to engage or disengage the wheel. Thus the plate J may be firmly secured to the wheel G, by 45 fixing the buttons and screwing down the nuts on bolts K, in any position desired relative to the handle. By means of the different angles of the blade this plow is adapted to do a great variety of work in both right and left handed 50 plowing.

What I claim as my invention, and desire to secure by Letters Patent, is—

1. The combination, with a trapezium-shaped plow-blade sharpened at its four edges, 55 concave, and centrally perforated, of a cylindrical standard, E, a shank, F, having a socket therefor, and a set-screw, m, and a bolt securing the shank reversibly to the center of the said blade, substantially as described, 60 whereby a plow-blade hung to present any side or corner forward may be turned around the standard to any angle with the line of travel, for the purpose set forth.

2. The combination, with the many-edged 70 blade J, of the beveled serrated wheel G, pivoted thereon, the shank F secured to the wheel G, and provided with a standard-socket, and the buttons H and I, having serrated edges and slots L, and the bolts K, substantially as shown 75 and described.

MYRON A. TWITCHELL.
